UNITED STATES PATENT OFFICE.

CHARLES O. CRISTALLINI, OF WORCESTER, MASSACHUSETTS, ASSIGNOR TO PECK SHOE COMPANY, OF WORCESTER, MASSACHUSETTS, A CORPORATION OF MASSACHUSETTS.

ARCH-SUPPORTING SHOE.

Application filed April 23, 1926. Serial No. 104,192.

This invention relates to a shoe having permanently mounted therein means for holding an arch in position.

The principal objects of the invention are 5 to provide a shoe having integral means therein for holding the arch support in place, to provide a construction in which the cushion can be adjusted transversely of the sole of the shoe by the wearer or a shoe salesman and in which it can be removed and replaced with another of a different size and shape without cutting or tearing any part of the shoe or otherwise injuring the shoe, especially the in-sole.

15 The invention is of advantage to the manufacturer, the retailer and the wearer.

Other objects and advantages of the invention will appear hereinafter.

Reference is to be had to the accompanying drawings in which

Fig. 1 is a plan of an in-sole constructed in accordance with this invention, right side up before it is attached to the upper;

Fig. 2 is a bottom plan view of the same;

25 Fig. 3 is a transverse sectional view of the completed shoe but showing only a fragment thereof;

Fig. 4 is an edge view of the in-sole by itself showing how the arch cushion is inserted;

30 Fig. 5 is a sectional view on an enlarged scale on the line 5—5 of Fig. 4;

Fig. 6 is a plan of a pad or cushion used in this construction;

35 Fig. 7 is an edge view of the same; and

Fig. 8 is a plan of the in-sole in position to be used showing the arch supporting cushion in dotted lines.

Although this invention is capable of use 40 with other types of shoes I have shown it as applied to a shoe constructed in accordance with my prior Patent No. 1,631,919, granted June 7, 1927. For this purpose I have shown, especially in the first three figures, the manufacture of a shoe of that type modified for this purpose. In these figures the in-sole 10 is smoothed down between rollers in the usual way and the inner channel 11 is formed as usual, leaving an inwardly 45 extending flap 14. I cut off the outer flap, leaving a horizontal ledge 12, all the way around the in-sole except at the heel. This furnishes a projection of uniform thickness as thin as may be convenient. It has an in-

55 ner vertical wall 13. The side of the in-sole shown in Fig. 2 is its bottom which preferably is the grain side of the leather.

I complete the in-sole by pasting to the upper surface of the toe portion beyond the dotted line 9, a surface lining 16 of calf-skin. This is not pasted between this line 9 and the heel. It has a flange 17 projecting beyond the in-sole 10 and around the toe portion only and beyond the line 9.

In the manufacture of the shoe, the upper 65 18 and its lining, if used, are applied to the in-sole as described in my above mentioned application and where the flange 17 is located they are in contact with it. They are brought down around the edge of the in-sole and sewed to the outer surface and the welt 20 by a line stitching 19 from the channel 11. The welt is secured to the outer sole 70 23 in the usual way with a lining 22 on top of the out-sole, if desired.

75 This description so far relates largely to the toe part of the shoe, although the rest of it is manufactured in the same way so far as possible in the absence of the flange 17. Now this calf-skin 16 on which the flange 17 80 is located is made of the usual shape back of this flange. As stated, it is not cemented to the in-sole 10 in the rear and center parts but lies in the shoe over these parts. It is secured at the rear by a separable fastening 85 25 of any desired type. This fastening is let into recesses 26 in the in-sole and 27 in the part of the out-sole which extends over the heel 28 so that it will not cause a projection that would make the shoe uncomfortable at the heel. The separable fastening is formed of two parts, one of which is secured to the lining 16.

90 It will be seen therefore that this lining can be attached at the rear and brought upwardly as shown in Fig. 4. This permits of the insertion of an arch supporting cushion 20. This may be of any desired kind or type. I have shown it in the form of a single piece of felt of a general triangular form with rounded points and with a flat upper surface and inclined sides, but these cushions can be formed of any material and made in any shape to suit the wearer.

95 100 105 The cushion is inserted near the shoe at the particular joint where it is needed. It is moved from the rear up toward the point where the lining 16 is cemented to the in-sole

and that forms the line 9 along which it can be adjusted sidewise for most patients. If it is not found to be in exactly the right place after being tried, the lining 16 can be 5 raised and the cushion moved over from one side to the other.

A practical advantage of this shoe is that the shoe itself does not have to be made with the arch support in position, but is sent to 10 the retailer without any support whatever.

The retailer then fits his customer right in the store by trial and the customer does not take the shoe until he has the arch support in the position which seems to be the proper 15 one. If after wearing it a short time he finds it is not exactly in the right place, he can either adjust the cushion himself or take it back to the store and have it adjusted for him. This may be done as many times as 20 may be necessary without injury to the shoe and without the necessity of re-shaping the support or detaching it with difficulty and then trying to paste it in again in the right place.

25 It will be seen therefore that this constitutes a great convenience to the wearer and enables the retailer to buy shoes of each size all alike and then to fit them to any customer who has arch trouble with a

30 metatarsal arch. The retailer can correct all mistakes or any difficulty that may arise later from the shifting of the pad, although the latter is not likely to happen as the lining is held down tightly by the fastening at

35 the heel. It is, of course, possible to paste the cushion on the top of the in-sole and paste down the lining along its edges, if it is desired so that one may be sure that there will be no shifting of the pad after it is

40 worn. This should be done only after a proper trial, although by simply pasting the in-sole along its two edges, it can be detached very readily and pasted over again if desired. If it is to be pasted, it is possible

to leave out the fastening at the heel but if 45 constructed in the preferred form as described above, this will not furnish any projection that would cause any discomfort to the wearer and it is preferred to use it.

It will be seen therefore, that this arrangement is of advantage to the manufacturer, salesman and wearer and that it can be produced at substantially the same expense as the corresponding shoe without it.

50 Although I have illustrated and described only a single form of the invention I am aware of the fact that it can be applied to any type of shoe other than the one described and that modifications can be made by any person skilled in the art without departing from the scope of the invention as 55 expressed in the claims. Therefore I do not wish to be limited in this respect, but what I do claim is:—

1. As an article of manufacture, a shoe 65 having a lining over the in-sole provided with an integral flange around the toe portion secured in position under the edge of the upper all around the toe portion to help hold it in position and permanently free 70 from the in-sole from the rear end of said flange to the extreme rear of the shoe.

2. A shoe having a lining over the in-sole provided with a flange around the toe portion secured in position under the edge of 75 the upper at the toe of the shoe, the lining being secured to the in-sole along their contacting surfaces around the toe portion up to a straight line across the shoe at the front end of the metatarsal arch and free at the 80 rear of said line to provide a space in which an arch supporting cushion can be located under the lining and to limit the forward position of the cushion.

85 In testimony whereof I have hereunto affixed my signature.

CHARLES O. CRISTALLINI.
